UNITED STATES PATENT OFFICE.

JAMES CHRISTIAN ALEXANDER, OF ROSEBURG, OREGON.

COMBINED MILK EVAPORATOR AND DRIER.

986,118.

Specification of Letters Patent.

Patented Mar. 7, 1911.

Application filed May 10, 1910. Serial No. 562,183.

To all whom it may concern:

Be it known that I, JAMES C. ALEXANDER, a citizen of the United States, residing at Roseburg, in the county of Douglas and State of Oregon, have invented certain new and useful Improvements in Combined Milk Evaporators and Driers, of which the following is a specification.

My invention relates to a combined machine for making either condensed or powdered milk.

An important object of my invention is to provide a machine of the above character, which will render the process of powdering milk continuous and expeditious.

A further object of my invention is to provide a device of this character, which is simple in construction and positive in its operation.

A further object of my invention is to provide a machine for powdering milk, so constructed that the same may be employed to condense milk without altering its construction.

In the accompanying drawings forming a part of this specification and in which like numerals are employed to designate like parts throughout the same, Figure 1 is a central vertical section through the upper half of the machine. Fig. 2 is a similar view through the lower half of the machine. Fig. 3 is a detail fragmentary view of a portion of the endless belt, employed in the machine.

In the drawings illustrating a preferred embodiment of my invention, the numeral 1 designates sides of a hollow base or support 2, which are arranged upon a suitable foundation 3. Within the upper end of this hollow-support is arranged a crucible-shaped receptacle 4, having a flange 5, which is disposed upon and suitably secured to the sides 1. This crucible-shaped receptacle is further provided adjacent its bottom with a discharge pipe 5', which communicates with a suitable form of exhaust fan or pump (not shown). The crucible-shaped receptacle 4 is further provided with a door 6', whereby access may be had to the interior of the same. The open end of the crucible-shaped receptacle 4 is closed by means of a plate 6, which forms the bottom of an upright casing 7 constituting the body portion of the machine. The upright casing 7 is preferably square in cross section

and provided at suitable intervals with doors 9 and 11, whereby access may be readily had to the interior of the casing 7. The doors 9 and 11 may preferably be provided with sight openings whereby the operation of the machine may be observed. The upper end of the casing 7 is provided with an outwardly extending flange 14, upon which is seated a cover 15, which is bolted or otherwise secured thereto. This cover is provided with a curved pipe 16, which has communication with the casing 7 and a suitable form of suction pump (not shown). It is thus seen that a vacuum may be created within the casing 7 by means of the pipe 16, and the vapors given off from the material being evaporated within said casing will be accordingly withdrawn from the same through the pipe 16.

Within the upper portion of the casing 8 is arranged a plurality of evaporating pans 18, which are disposed in superposed relation, and alternate ones of which slope in opposite directions, so that the lower end of one pan will deliver its contents to the upper end of the pan below it. These evaporating pans are gradually arranged at a greater angle toward the lower portion of the casing 8, which is necessary to cause the thickened milk to travel over the same. The lowermost pan 18 has its lower end arranged to deliver its contents to a trough 19, which is provided with two discharge pipes 20 and 21. The discharge pipe 20 passes through the door 11, as shown at 22, and is provided with a valve 23 upon the outer side of the same. This discharge pipe 20 extends downwardly and communicates with a closed collecting tank 24, which is provided with a glass-tube gage 25, for indicating the level of the contents within the same. This collecting tank is further provided at its bottom with a cooling coil 26, and communication between this cooling coil and collecting tank is controlled by means of a suitable form of valve, as shown at 27. The cooling-coil 26 is arranged within a receptacle 29 and around the cooling-coil, may be placed a suitable cooling medium. The lower end of the coil 26 is controlled by means of a suitable valve, as shown at 30. The other discharge pipe 21 of the trough 19 is controlled by means of a valve as shown at 31, which may be opened or closed by the operator when the door 11 is opened.

A supply tank 31 is provided with a pipe 32, which extends through the cover 15 and is arranged to feed material upon the higher end of the uppermost evaporating-pan 18. 5 This pipe 32 is controlled by means of a suitable valve, as shown at 33.

Between the evaporating pans 18, are arranged steam-pipes 34, which are preferably disposed in horizontal and vertical rows, as 10 shown in Fig. 1. These horizontal rows of pipes are gradually spaced farther apart toward the bottom of the casing 8. The function of these steam pipes is to create sufficient heat within the casing 7 to evaporate the 15 liquid which is being fed on the evaporating-pans 18. It is to be understood that any suitable means may be employed to regulate the amount of steam fed into the pipes 34.

The casing 7 is provided upon one side 20 thereof with a device as shown at 35, for indicating the reduced pressure within the casing 7, and this casing is further provided upon its opposite side with a thermometer-device as shown at 36, for indicating the heat 25 temperature within the casing 7.

Within the casing 7 near its center and adjacent the lowermost evaporating pan 18 is arranged a plurality of spaced sprocket wheels 38, forming a horizontal row of the 30 same. These sprocket wheels are mounted upon shafts 39, which are suitably journaled through the casing 7. Near and above the plate 6, within the casing 7, is arranged a horizontal row of spaced felt-covered rollers 40, which are mounted upon shafts 41 journaled through the casing 7. The felt-covered rollers 40 are disposed in vertical alinement with the spaces between the sprocket-wheels 38 above referred to. Within 40 in the crucible-shaped receptacle 4, are arranged sprocket-wheels 42, which are rigidly mounted upon shafts 43 journaled through said crucible-shaped receptacle. The sprocket-wheels 42 are preferably in 45 horizontal alinement with each other and in vertical alinement with the outer sprocket-wheels 38 as clearly shown in Fig. 2. An endless belt 44 is trained about the sprocket wheels 38, 42 and the rollers 40 in a manner 50 clearly shown in Fig. 2. This endless belt is preferably formed of aluminum plate perforated and this belt is provided with a selvage edge 44^a. See Fig. 3. The selvage edge 44^a is formed of a sufficiently flexible metal, 55 and is provided with spaced openings 44^c to coöperate with the teeth of the sprocket-wheels 38 and 42. This endless belt passes through suitable openings 43 formed upon the plate 6.

60 For the purpose of actuating the metallic endless belt 44, one of the shafts 42 may extend outwardly through the crucible-shaped receptacle 4, and be provided with a fast pulley 45, which may be driven by means of 65 a suitable motor (not shown). The sprocket-

wheels 38 and 42 are rotated to cause the metallic endless belt 44 to move in the direction as indicated by the arrows.

Below the sprocket-wheels 38 are arranged vertical and horizontal rows of steam-pipes 70 56, these vertical rows being in alinement with steam pipes 34, and said horizontal rows being arranged closer together, toward the bottom of the casing 7, as clearly shown in Fig. 2. It is to be understood that any 75 suitable means is to be employed to regulate the supply of steam through the pipes 56.

Near and above the plate 6 are arranged felt covered rollers 46, which are in engagement with the metallic endless belt 44 80 passing between the same. The rollers 46 are pressed tightly against the endless belt 44 and against the plate 6 as shown, by means of springs or any suitable means (not shown). These rollers 46 are mounted upon 85 shafts 47 which are journaled through the casing 7. The function of the rollers 46 is to close the openings 43 whereby communication between the casing 7 and the crucible-shaped receptacle 4 is prevented, which will 90 permit of a suitable vacuum being maintained within the casing 7.

Within the crucible-shaped receptacle 4, above and below the endless belt 44, are arranged respectively rotary brushes 49 and 95 50, having metallic bristles 51 as shown, which engage the metallic endless belt 44. These brushes 49 and 50 are driven in opposite directions to each other in order to brush off and pulverize the dried milk arranged 100 upon the perforated metallic belt 44. The crucible-shaped receptacle 4 is provided with a plurality of air-inlets 52, in order to allow cool air to enter within the same to cool the milk powder and facilitate the action of 105 the suction fan to remove the same.

The discharge pipe 21 above referred to is arranged to deliver its contents within a trough 54 which is provided with a longitudinal opening 55, and acts as a spreader 110 to deliver material upon the metallic endless belt 44.

In the operation of the device, milk is fed from the supply tank 31 upon the uppermost evaporating pan 18, and this milk will 115 accordingly gravitate toward the lowermost pan 18. The milk while traveling upon the evaporating pans is subject to heat given out from the steam pipe 34, whereby this milk is partially evaporated or condensed. This 120 condensed milk may then be withdrawn by opening the valve 23, which allows the condensed milk to run into a collecting tank 24, from which it may be passed through the cooling coil 26. If, however, it should 125 be desired to reduce the original milk to a powdered form, the valve 23 is kept closed and the valve 31 is opened, whereby the partially evaporated or condensed milk is 130 permitted to be fed upon the perforated

metallic endless belt 44. This milk is moved through the casing 7 by the belt 44, and at the same time subjected to heat from the steam pipes 56. By this operation the milk is reduced to a powder, and removed from the endless belt 44, by means of the rotary brushes 49 and 50. The powdered milk when removed from said endless belt, is subjected to cool air, which is being drawn through the receptacle 4, and said powdered milk is removed from said receptacle together with this cool air.

Special attention is called to the fact that the metallic belt 44 is perforated which causes the milk to stick to the same. The milk is dried by the heat given off from the steam pipes, and owing to the location of said pipes the milk could not become scorched.

20 It is to be understood that although my apparatus is particularly adapted to be used for the treatment of milk as above described, the same may be successfully employed to evaporate salt water gelatin, glue or other 25 fluids.

Having fully described my invention, I claim.

1. In a device of the character described, a casing, a plurality of angularly disposed 30 evaporating pans arranged therein to deliver material from one to the other, and an endless belt arranged within said casing to receive material from said evaporating pans.

2. In a device of the character described, 35 a casing, a plurality of evaporating pans arranged therein, and an endless belt arranged within said casing to coöperate with said evaporating pans.

3. In apparatus of the character described, 40 a casing, a perforated metallic endless belt arranged therein, means for feeding material upon said endless belt, heating means arranged within said casing, means for exhausting air from said casing, and brushes 45 for coöperation with said endless belt.

4. In a device of the character described, 45 a casing, a plurality of superposed evaporating pans arranged therein, said evaporating pans being arranged so that material will 50 tend to travel faster on each successive lower evaporating pan, an endless belt arranged below said evaporating pans, and heating means arranged within said casing.

5. In a device of the character described, 55 a casing, a plurality of evaporating pans angularly disposed within said casing and adapted to deliver material from one to the other; a perforated metallic endless belt arranged below said evaporating pans for 60 receiving material therefrom, a closed receptacle through which said endless belt travels, and means for removing material from said endless belt to discharge the same within said closed receptacle.

6. In a device of the character described,

a casing, evaporating pans arranged therein, an endless belt arranged within said casing to coöperate with said evaporating pans, heating means associated with said casing, and means for removing material from said 70 endless belt.

7. In a device of the character described, a casing, evaporating pans arranged therein, an endless belt arranged below said evaporating pan to coöperate with the same, a 75 closed receptacle through which said endless belt passes, means for removing material from said endless belt, and means for exhausting air from said closed receptacle.

8. In a device of the character described, 80 a casing, evaporating pans arranged therein, an endless belt arranged below the same to coöperate therewith, a closed receptacle through which said endless belt passes, brushes arranged within said closed receptacle to engage said endless belt, and means for exhausting air from said closed receptacle.

9. In a device of the character described; 90 a casing, an endless belt arranged therein, means for feeding material to said endless belt, heating means arranged within said casing, a closed receptacle through which said endless belt passes, and means for removing material from said endless belt. 95

10. In a device of the character described, 100 a casing, a plurality of approximately horizontally arranged superposed evaporating pans arranged within said casing, superposed approximately horizontally disposed rows of pulleys arranged within said casing below said evaporating pans, an endless belt trained about said pulleys, a closed receptacle through which said endless belt travels and means for removing material 105 from said endless belt.

11. In a device of the character described, 110 a casing, an inclined evaporating pan arranged therein, an endless belt arranged within said casing to receive material from said evaporating pan, and heating means arranged within said casing.

12. In a device of the character described, 115 a casing, an evaporating pan arranged therein, an endless belt arranged within said casing to receive material from said evaporating pan, and means for removing material from said endless belt.

13. In a device of the character described, 120 a casing, an inclined evaporating pan arranged therein, an endless belt arranged within said casing to receive material from said evaporating pan, heating means associated with said casing, a closed receptacle through which said endless belt passes, and means for removing material from said endless belt. 125

14. In a device of the character described, 130 a casing, an evaporating pan arranged therein, a movable belt arranged to receive mate-

rial from said evaporating pan, and heating means for said casing.

15. In a device of the character described, a casing, a plurality of superposed inclined evaporating pans disposed within said casing, heating means associated with said evaporating pans, and the inclined position of each successive evaporating pan being steeper, to cause material to travel at approximately the same rate of speed upon each successive pan, after such material has become condensed.

16. In a device of the character described, a casing, a plurality of superposed inclined

evaporating pans disposed within said casing to deliver material from one to the other, means to feed material to said evaporating pans, heating means associated with said evaporating pans, the inclined position of each successive lower evaporating pan being steeper, and means to exhaust air from said casing.
